RAILWAY HIGHWAY-VEHICLE CARRIER

George S. Goodwin and Peter Kass,
Chicago, Ill.

Application November 17, 1937, Serial No. 175,010

6 Claims. (Cl. 105—159)

This invention relates to railway rolling stock and particularly to cars for transporting vehicles operable on highways either under their own power or as trailers to be drawn by trucks or tractors.

Such vehicles are used to pick up a load and transport it from point of origin to a convenient railroad terminal and there the vehicle is run on to a railway car, then forwarded by the railway 10 car to another terminal where the vehicle is transferred to the highway to deliver its load to destination.

Among the problems encountered in such system of transportation is the movement of trailers 15 endwise of the car either from one car to another or from or onto loading platforms or ramps adjacent the end of the car. This movement of the vehicles will take place usually at railroad terminals where a plurality of cars will have a plurality of trailers movable into position thereon. One of the objects of the present invention is to facilitate movement of a highway vehicle from 20 one car to another.

Another object of the invention is to adequately support the body of the highway vehicle directly from the floor of the railway car thereby relieving the vehicle landing gear of the load during transportation by rail.

In attaining this object we provide an upstanding vehicle supporting structure and it is a further object of the invention to construct such a support so that if it is left in functioning position when there is no trailer on the car, the support will not interfere with the movement of a trailer 35 on to the car.

Another object of the invention is to secure the trailer against movement longitudinally of the carrier and it is preferable that the vehicle securing means be adjustable longitudinally of the 40 carrier to accommodate different lengths of vehicles and different diameters of wheels.

Another object of the invention is to facilitate the anchoring of the vehicle to the carrier.

These and other detailed objects of the invention are attained by the structures illustrated in the accompanying drawings, in which—

Figure 1 is a top view of a railway car embodying the invention, a portion of an adjacent car and the connecting apron being shown.

Figure 2 is a side elevation of the structure shown in Figure 1 with two highway trailers in position thereon.

Figure 3 is an end view of the carrier with a vehicle mounted thereon and showing in section

the apron intended to connect the carrier with an adjacent carrier.

Figure 4 is a vertical transverse detail section taken on the line 4—4 of Figure 3.

Figure 5 is a horizontal detail section taken on the line 5—5 of Figure 3.

Figure 6 is a vertical transverse detail section taken on the line 6—6 of Figure 1.

Figure 7 is a section through the same structure showing the parts in a different position. 10

Figure 7a is a detailed top view of parts shown in Figure 7.

Figure 8 is a detail section taken substantially on the line 8—8 of Figure 6.

Figure 9 is a longitudinal section through a 15 portion of the car floor showing in side elevation a detail of a device for arresting movement of the vehicle longitudinally of the carrier.

Figure 10 is an end elevation of the same.

Figure 11 is a top view of one corner of a car 20 embodying modifications of the structures shown in Figures 1 to 10, parts of the structure being broken away to show the remaining parts on a larger scale.

Figures 12, 15, 16 and 17 are detail sections 25 taken on the corresponding section lines of Figure 11, Figure 17, however, showing the parts in a different position than that occupied in Figure 11.

Figures 13 and 14 are detail sections taken on 30 the corresponding section lines of Figure 12.

Figure 18 is a side elevation of the jack shown in Figure 11.

Figure 19 is an end elevation of the structure shown in Figure 18. 35

Figure 20 is a longitudinal vertical section through the end of the car shown in Figure 11 and the corresponding portions of an adjacent car and the interconnecting platform plate with the supporting structure shown in elevation except for a small portion which is sectioned for clearer illustration. 40

Figure 21 is a transverse vertical section taken approximately on the line 21—21 of Figure 20 but showing the supporting bracket moved to a different position. 45

Figure 22 is a top view of a modified vehicle-arresting structure.

Figures 23, 24, and 26 are detail sections taken on the corresponding section lines of Figure 22. 50

Figure 25 is a detail section taken on the line 25—25 of Figure 23.

The car illustrated has the general appearance of an ordinary flat car and includes side sills 1, end sills 2, and a floor 3. Pockets 4 at intervals 55

along sills 1 receive stakes 6 which carry stringers 7 forming safety guards or retainers for the highway vehicle wheels 8.

The entire floor may be covered by steel plates 9 or restricted portions only of the floor beneath the normal position of the highway wheels 8 may be provided with plates 9.

An apron is provided at one end of each car and comprises a plate 10 preferably hinged to the end sill by U-bolts as indicated at 11 (Figure 1) and movable from the upright position shown at the left hand end of Figure 2 to the horizontal position indicated at the right hand end of Figure 1 and in Figure 3. Plate 10 may be reinforced by angular elements 12 and 13 extending lengthwise of the car and also by a transverse member 14 preferably arranged to rest upon the head or shank of a coupler structure 15 which will be carried in or from the end sill in the usual manner. Additional support for the apron is provided by brackets 16 here shown as slidable through recesses 17 provided in end sill 2 and each arranged to be retained in projected position or in retracted position by a latch 18 pivotally suspended from the sill and adapted to be engaged by one or more stops 19 projecting laterally from the bracket 16.

When in projected position, the outer edge of each bracket is received in a recess in the end sill 2a of an adjacent vehicle. A channel-like track 35 is secured to end sill 2 and extends inwardly therefrom to support bracket 16 when the same is retracted.

During loading or unloading of the car, the brackets will be extended and the apron will be lowered and supported by the brackets and from the car end sill and coupler structure as well as by the adjacent platform or car end. When the vehicles have been loaded upon the car, the apron will be raised and held in raised position by a latch 20 pivoted on an upright stake 21.

Near one end of the car and also near the center of the car, plate 9 and the top floor section are cut away as indicated at 22 (Figures 6 and 7), and a plate 23 forms the bottom of each recess. A vehicle supporting jack, comprising a body member 24 and a screw threaded extension 25, has a base plate 26 which rests upon plate 23 to stably support the jack structure in functioning position. A dowel 27 on the bottom of plate 26 may be inserted in any selected one of a number of openings 28 in plate 23 to position the jack as desired longitudinally of the car. Gussets 32 brace member 24 and plate 26. A pair of spaced Z-bars 29 are secured to the edges of plate 23 and the inturned upper flanges of Z-bars 29 cooperate with plate 23 to form spaced guides for blocks 30. A rod 31 having its end secured to blocks 30 passes through one of the gusset plates 32 to hinge the jack structure to the floor.

When a vehicle is placed upon the car, the jack is raised to upright position and extended until it engages the framing 33 of the vehicle and relieves the trailer landing gear 34 of the weight of the vehicle and its load. If a vehicle being moved onto the car strikes a jack which has been left upstanding, the jack will pivot on its hinge 30-31 and be thrown to the floor, as indicated in Figure 7. If it is preferred that the jack be held upright, one or more pawls 26a may be pivotally mounted on plate 26 and, when the jack is upright, may be rotated as indicated in Figure 7a to engage the upper flange of one of the Z-bars 29 to secure the jack.

It is customary to anchor the vehicles to the car, and anchoring chains for this purpose are indicated at 45 and 46, chains 45 extending generally longitudinally of the car from the trailer to the floor to prevent too great longitudinal thrusts on the springs and tires of the vehicle, and chains 46 holding the vehicle down and preventing side sway.

Adjacent each chain 46 there is provided preferably a bracket plate 47 attached to side sill 10 1 and extending upwardly above the top of the sill and inclined inwardly beneath stringers 7, the latter and the corresponding portion of the floor being recessed for brackets 47. A stirrup 48 has its ends secured to bracket 47 and intermediate its ends receives the end link 49 of the anchoring chain 46. Link 49 may be slid along stirrup 48 to the point most nearly opposite the point of attachment of the chain to the vehicle, thereby providing for a direct outward pull. If stirrup 48 is corrugated as shown, it will tend to resist shifting movement of link 49 along the same.

Usually it is desired to supplement the longitudinally extending anchoring chains 45 with 25 chock blocks between the vehicle wheels and the car floor. Figures 9 and 10 illustrate a simple form of block 50 having an anchoring plate 51 perforated to receive a holding pin 52. The car floor is provided with a chock block supporting plate 53 having a series of apertures 54 in any one of which pin 51 may be inserted to hold the chock block against movement longitudinally of the car. Two blocks 50 may be separately secured along plates 53 to accommodate different 35 locations of the vehicle wheel or different sizes of wheels.

Figures 11 to 21 illustrate a modified structure illustrating the same general arrangement indicated in Figures 1 and 2. The portions of the 40 floor which would support the trailer wheels are recessed as shown at 60 and a wheel seating casting or pressing 61 is received in the recess and supported at the edges thereof. Chock devices 62 and 63 are hinged at 64 and 65 respectively 45 to seat member 61 and may be swung to the wheel-engaging position shown in full lines in Figure 12, or to the positions indicated by the dot and dash lines.

Chock 62 comprises a ribbed frame and a 50 wooden filler. When in elevated position, the frame back plate 66 rests upon the top surface of the car floor 67 with the wooden filler 68 in position to engage a wheel resting in the curved portion 69 of the seat plate. When the chock is 55 moved to non-functioning position, filler 68 and the ribs 70 of the frame extend downwardly into the recess afforded by the wheel seat and the outer edge 71 of the back plate rests upon a suitable ledge 72 provided therefor in the wheel 60 seat.

Chock 63 comprises a frame and a wheel-engaging device adjustably mounted thereon. The frame includes a back plate 73, side webs 74 and an upwardly inclined front plate 75 bifurcated 65 by a slot 76. A slide 77 rests upon a suitable track provided therefor in the front face of plate 75 and a clamping bolt 78 extends through slide 77 and slot 76 and is provided with a clamping nut 79 whereby the slide may be held in adjusted 70 position on plate 75. A wheel-engaging element 80 is pivoted at 81 on slide 77 and this structure adapts the chock arrangement to firmly engage wheels of different sizes to firmly hold the same against movement longitudinally of the vehicle. 75

When functioning as described, back plate 73 will rest upon a horizontal portion 82 of seat member 61. When the chock is not in use, its upwardly projecting portions are received in the seat member recess 83 and the edge 73a of the back plate rests upon a ledge 84 on member 61. When the chock elements are inserted in the recesses 83, the back plates 66 and 73 form a smooth continuation of the floor surface over which the trailer 5 and its tractor may travel until the trailers are positioned near their anchoring point, whereupon the chock members 62 may be swung up into functioning position, the vehicle backed into recess 60, and chock member 63 is swung into functioning position with its elements 77 and 80 adjusted to secure the wheel against movement.

The modified jack indicated in Figure 11 and detailed in Figures 18 and 19 includes a heavy braced frame comprising cross pieces 85, uprights 86 and diagonals 87, there being a pair of screws 88 threaded into supporting collars 89 carried on the framework. The cross beam or yoke 90 rests on the top of screws 88. Projecting from the bottom cross bar 85 are dowels 91 adapted to be inserted in a selected pair of openings 92 (Fig. 11) provided in floor plate 93 corresponding to plate 9 in Figures 1 and 3. By shifting elements 91 to different pairs of openings, the jack may be placed to accommodate different lengths of vehicles. A link 94 may be provided on each side of the frame for attachment of anchoring chains to hold the jack in upright position. This jack may be placed, where required, beneath the forward portion of the trailer and screws 88 rotated separately by handles 95 to bring cross beam 90 into supporting contact with the under-frame of the trailer.

The support structure for the apron 96 is shown in Figures 11, 20 and 21 in which each car end sill 97 has a bracket 98 hinged thereto and arranged to be projected outwardly from the sill beneath the apron stiffener 99 to support the apron throughout half of its length, the other half being supported on the end sill of the adjacent car. When the brackets are projected towards each other, their outer ends may be held together by dropping a key K into the opposing slots in the ends of the brackets. When not in use, brackets 98 may be moved back against the end sill and held in retracted position by a latch plate P pivoted on the end sill.

Figures 22 to 26 illustrate a modified chock structure which may be substituted for the body of the chock shown at the left of the wheel in Figure 12. This structure provides a greater degree of adjustment of the device than obtainable with the structure shown in Figure 12. The left hand portion 100 of the wheel seat member includes bearings 101 projecting outwardly from its side walls and blocks 102 are slidably along bearings 101 and are retained in position thereon by cap plates 103. Bearings 101 and cap plates 103 have aligned apertures 104 for receiving pins 105 which may be inserted through the apertures and through a corresponding opening in blocks 102, thereby holding the blocks in adjusted position lengthwise of the wheel receiving recess. The main frame member of the chock is indicated at 106 and is pivoted at 107 to sliding blocks 102. Member 106 will mount a wheel engaging element similar to that shown at 77 and 80 in Figures 12 and 14.

The various modifications may be used extensively interchangeably with each other and, if

desired, both forms of jacks, chock blocks and apron supports may be used on the same car.

The structure described provides for the free movement of tractors and trailers over the car from or onto a platform, ramp, or adjacent car, and a ready securing of the trailer wheels in position on the car and adequate support for the other end of the trailer. All of the securing and supporting parts may be manipulated into and out of operating position easily. The construction readily adapts the car for vehicles having different lengths and wheel sizes, hence the general objectives indicated at the beginning of the specification are attained. While the structure and equipment described adapt the car for a special service, the car may be utilized for the usual flat car loadings. The chains and jack members may be removed readily or may be placed in a well in the floor or otherwise disposed of.

All details of the drawings and description are to be considered as illustrative only and not as limiting the scope of the invention as expressed in the claims except as some of the claims are directed to specific features. Other modifications may be made freely by those skilled in the art without departing from the spirit of the invention and the exclusive use of such modifications as come within the scope of the claims is contemplated.

What is claimed is:

1. In a car of the class described, a floor having a wheel receiving pit, a member pivoted to said floor at one side of said pit and movable about its pivot to a position within said pit or to a position over said floor adjacent to said pit, said member having a straight face arranged to form a continuation of the top surface of said floor when said member is in said first mentioned position or to lie along said floor when said member is in said second mentioned position, and said member having a concave face at an angle to said straight face and disposed, when said member is in the latter mentioned position, to form a chock face for a wheel seated in said pit.

2. In a car of the class described, a floor structure provided with substantial recesses spaced apart longitudinally of the car, and chock block structures pivotally mounted on said floor and arranged to be moved about their pivots into positions in which they fit respectively in said recesses or into positions in which they project above said floor at opposite sides of one of said recesses to engage opposite edges of a wheel seated in that recess.

3. In a car of the class described, a floor member comprising an interior structure forming a recess for receiving the wheel of a vehicle carried on the car, there being a chock block structure pivoted to one side of said member and movable to a position, in which it overlies the adjacent floor section and will project upwardly therefrom to engage the edge of a wheel seated in said member, or to a position in which the wheel-engaging element is received in said member and the structure forms a continuation of the floor surface, said member having a ledge spaced from the pivotal mounting of said structure to support the edge of the latter when it is swung about its pivot to the latter-mentioned position.

4. In a car of the class described, a floor portion, and a chock block member extending upwardly therefrom at an incline from the vertical, and a wheel-engaging element slidably and pivotally mounted upon said member to render the

latter adjustable for tightly engaging different diameter wheels of vehicles carried by the car.

5. In a car of the class described, a floor portion, a member providing a recess in said floor portion, a chock block structure slideable along said member longitudinally of said floor portion and pivoted on said member to swing into the depression formed by said member or upwardly and away from said depression to rest upon said

10 floor portion.

6. In a car of the class described, a floor portion, a member providing a recess in said floor

portion and having bearing tracks at its opposite sides, blocks slideable in said bearing tracks, means for securing said blocks to said tracks at different points along the same, a chock block structure pivoted on said blocks and slideable therewith and movable from an upwardly projecting wheel-engaging position to a downwardly projecting position in which it may be received in said recess.

GEO. S. GOODWIN. 10
